UNITED STATES PATENT OFFICE.

THOMAS H. HINDLE, JR., OF NEW YORK, N. Y.

DESIGN FOR A DOLL.

47,361.

Specification for Design.

Patented May 18, 1915.

Application filed February 11, 1915. Serial No. 7,607. Term of patent 7 years.

To all whom it may concern:

Be it known that I, THOMAS H. HINDLE, Jr., a citizen of the United States, residing in the city of New York, borough of Brooklyn, in the county of Kings and State of New York, have invented a new, original, and ornamental Design for a Doll, of which the following is a specification, reference being had to the accompanying drawing, forming part thereof.

The figure is a perspective view of a doll showing my new design.

I claim:

The ornamental design for a doll as shown.

THOMAS H. HINDLE, JR.
